UNITED STATES PATENT OFFICE

ABRAHAM M. KATZ, OF BROOKLYN, NEW YORK, ASSIGNOR TO IDEAL NOVELTY & TOY COMPANY, OF BROOKLYN, NEW YORK, A CORPORATION OF NEW YORK

DOLL CONSTRUCTION

Application filed February 26, 1932. Serial No. 595,408.

My invention relates to a new and improved doll construction.

One of the objects of my invention is to provide a simple device whereby the inner end of the limb of a doll can be suitably connected to the hollow body of a doll.

Another object of my invention is to provide an extremely simple and efficient construction.

10 Other objects of my invention will be set forth in the following description and drawing which illustrate a preferred embodiment thereof.

Fig. 1 is a perspective view showing the 15 invention applied to the leg of a doll.

Fig. 2 is an end view.

Fig. 3 is a sectional view.

The hollow leg L of the doll is preferably made of resilient rubber. The inner end of 20 the leg is provided with an opening in which a rigid button is located. This rigid button may be made of wood, metal or the like. This rigid button has a base 1 and an outwardly flaring head 2. The inner end of the head 2 is rounded and this head 2 generally has a frusto-conical shape. The rubber inner end of the leg L is provided with a rubber rib R which tightly engages and interlocks with the base and head of the button. When the 30 head 2 of the button is forced through the opening provided in the inner end of the leg of the doll, said opening end is expanded and the resilient rubber thereupon tightly engages the button. A hook H has its shank 35 passing through the rigid button and the inner end of this hook is provided with an enlarged head 3 so that the hook cannot be pulled through the button. A device or voice

40 V may be located in the head 2, so that a sound is produced when the hollow leg L is squeezed. The hook H can be connected to an elastic cord or the like which is located in the hollow body of the doll, whereby the 45 leg is held in position with respect to the body of the doll.

I have shown a preferred embodiment of my invention, but it is clear that numerous changes and omissions could be made without departing from its spirit.

I claim:

1. In a doll, a member having an inner end provided with an opening, said inner end being made of resilient material, and a button located in said opening, said button having a base and a tapered head, the base being of greater diameter than the inner end of said head, the base being also of greater diameter than said opening, said head filling said opening, said base being located behind the inner end of said opening, said resilient material being shaped so as to interlock with said head and said base and to press against said tapered head.

2. In a doll, a hollow and squeezable limb having an inner end provided with an opening, said inner end being made of resilient material, and a button located in said opening, said button having a base and a tapered head, the base being of greater diameter than the inner end of said head, the base being also of greater diameter than said opening, said head filling said opening, said base being located behind the inner end of said opening, said resilient material being shaped so as to interlock with said head and said base and to press against said tapered head, said button having a sound-producing device located therein, said sound producing device being operated by the air current which is produced when said limb is squeezed.

In testimony whereof I affix my signature.

ABRAHAM M. KATZ.
